WALL RACK FOR TOILET ARTICLES OR THE LIKE

Homer W. Miller, Sherman, Tex.

Application December 21, 1953, Serial No. 28,160

Term of patent 7 years

(Cl. D4—3)

Fig. 1.

Fig. 2.

Fig. 3.

I claim:

The ornamental design for a wall rack for toilet articles or the like, substantially as shown.
